1971. Divided and this application Mar. 25, 1971,
Ser. No. 128,225

Term of patent 14 years

Int. Cl. D8—06

U.S. Cl. D8—166

FIG 1

FIG 2

FIG 3

FIG 4

FIG. 1 is a front view of a pull showing my new design.
FIG. 2 is a top view of the pull as seen from the top of FIG. 1.

FIG. 3 is a side view of the pull as seen from the left of FIG. 1.

FIG. 4 is an enlarged sectional view taken along the line 4—4 in FIG. 1.

This application is a division of my copending application Ser. No. D. 24,455, filed Aug. 12, 1970, now Patent No. D. 222,233, Oct. 12, 1971.

I claim:
The ornamental design for a pull, as shown.
